(57) CLAIM

I claim, the ornamental design for a table, as shown and described.

DESCRIPTION

FIG. 1 is a perspective view of a table, showing our new design;

FIG. 2 is a side view thereof, the opposite side view being a mirror image thereof;

FIG. 3 is a front view thereof, the opposite rear view being a mirror image thereof;

FIG. 4 is a top view thereof;

FIG. 5 is a bottom view thereof;

FIG. 6 is a perspective view thereof, showing a second embodiment of my new design;

FIG. 7 is a side view thereof, the opposite side view being a mirror image thereof;

FIG. 8 is a front view thereof, the opposite rear view being a mirror image thereof;

FIG. 9 is a top view thereof; and,

FIG. 10 is a bottom view thereof.
